CLAIM

The ornamental design for a pen/printer interconnect
segment of a flexible cable for a printer, as shown and
described.

DESCRIPTION

FIG. 1 is a perspective view of a pen/printer intercon-
nect segment of a flexible cable for a printer, showing
our new design;

FIG. 2 is a front elevation view thereof;

FIG. 3 is a top plan view thereof;

FIG. 4 is a rear elevation view thereof;

FIG. 5 is a bottom plan view thereof;

FIG. 6 is a left side elevation view thereof; and,

FIG. 7 is a right side elevation view thereof.
